UNITED STATES PATENT OFFICE.

FRANK P. SHEPARD, OF EDMOND, OKLAHOMA TERRITORY, ASSIGNOR TO
THE OLIVER TYPEWRITER COMPANY, OF CHICAGO, ILLINOIS, A COR-
PORATION OF ILLINOIS.

DEVICE FOR INDICATING THE PRINTING-POINT ON TYPE-WRITERS.

No. 837,588.

Specification of Letters Patent.

Patented Dec. 4, 1906.

Application filed April 4, 1904. Serial No. 201,464.

To all whom it may concern:

Be it known that I, FRANK P. SHEPARD, a citizen of the United States, residing at Edmond, in the county of Oklahoma and Territory of Oklahoma, have invented certain new and useful Improvements in Devices for Indicating the Printing-Point on Type-Writers; and I do hereby declare that the following is a full, clear, and exact description thereof, reference being had to the accompanying drawings, and to the letters of reference marked thereon, which form a part of this specification.

This invention relates to an improved attachment for type-writers, and it relates more especially to a device for indicating to the eye the point upon which the type strikes the paper.

The invention is more especially applicable to type-writers of that kind known as the "Oliver," but is adapted for use in other forms of visible-writing machines, or those on which the printing-point is visible to the operator during the progress of the printing.

This invention may be more readily understood by reference to the accompanying drawings, in which—

Figure 1 is a view showing in central vertical section some of the principal parts of an Oliver type-writer equipped with my improvement. Fig. 2 is a plan view of an attachment embodying my invention, together with a ribbon-guide, platen, and scale-bar such as are ordinarily used in an Oliver type-writing machine. Fig. 3 is a sectional view taken upon line 3 3 of Fig. 2. Fig. 4 is a plan section taken upon line 4 4 of Fig. 3. Fig. 5 is a perspective view showing the upper portion of the supporting-arm by which is sustained the ribbon-shifting devices of an Oliver type-writer. Fig. 6 is a perspective view showing the parts embodying my invention detached from said supporting-arm to which they are normally secured. Fig. 7 is a face view of the under side of the device illustrated in Fig. 6.

As shown in the drawings, Fig. 1, A indicates the platen; B, the scale-bar; C, the reciprocating ribbon-guide; L, one of the type-bars; M, a key-lever; N, a connecting-rod joining the key-lever with the type-bar; O, the universal bar, and P the ribbon-guide-actuating lever connected with the universal

bar by a link Q, having at its lower end a slot q, which is engaged by a stud o with the universal bar. Said ribbon-guide has two guide-loops c c, through which pass the inking-ribbon, and it has a horizontal movement toward and from the platen, so as to carry the ribbon over the printing-point and away from the same. D indicates the supporting-arm for the ribbon-guide-actuating devices located in front of the platen and provided with a base-plate D'. E is a crank-shaft which is mounted upon and extends horizontally across the top of the base-plate D' and is mounted in two lugs d d, which rise from said base-plate. Said crank-shaft E is provided with an upwardly-extending rigid arm E', having pivotal connection at its upper end with the ribbon-guide C. Said crank-shaft is also provided with a crank e, to which is connected a vertically-reciprocating actuating-rod F, which is pivoted at its lower end to the lever P and through which oscillatory motion is given to the crank-shaft E and the ribbon-guide. The forward or outer end of said ribbon-guide is connected with the base-plate D' by means of a link G, which is pivoted at its upper end to the said ribbon-guide and at its lower end to lugs d' d' on the base-plate D', said link being parallel with the arm E' and serving to maintain the ribbon-guide in a horizontal position during its oscillatory movement. So far as described the devices shown are like those heretofore used on the Oliver type-writing machines.

Now referring more particularly to the features constituting my invention, H indicates a vertically-arranged rock-shaft which is pivotally supported on the arm D and is provided at its upper end with a horizontally-arranged pointer or indicating-arm h, adapted to extend over the top of the platen, with its free end adjacent to the printing-point and adapted for lateral oscillation through the turning of the said shaft H. Said indicating-arm stands normally at right angles to the platen or printing-line, with its free end or point, opposite or in line with the printing-point, but is adapted to be swung laterally away from the printing-point at each stroke of the type-bars, so that it will at such times be out of the way of and will not interfere with the types in making the impression. Mounted on the said base-plate D'

is a horizontal rock-shaft I, which extends in a direction parallel with the platen near the lower end of said rock-shaft H. The rock-shaft I is provided with an upwardly-extending rigid arm i, while the rock-shaft H is provided with a laterally-extending arm h', adapted for contact with the free end of the arm i. Said horizontal rock-shaft I is also provided with a horizontally-extending actuating-arm i', which extends over and bears upon the upper end of the crank-arm e of the rock-shaft E. These parts are so arranged that at the time the actuating-rod F rises, thereby swinging the end of the crank-arm e upwardly, the actuating-arm i' will be lifted and the rock-shaft I turned in a direction to swing the upper ends of the arm i thereof toward the arm h' on the rock-shaft H, and thus swing or move the latter in a direction to carry the indicating-arm h away from the printing-point. Movement of said rock-shaft H in a direction to carry the indicating-arm h in the opposite direction or toward the printing-point is afforded by means of a spring J, suitably applied to act on said rock-shaft H. Movement of said rock-shaft under the action of said spring J is limited by means of the stop-arm h² on said shaft, which arm is adapted for contact with adjacent stationary parts, so as to hold the said arm normally at the printing-point.

In the particular construction herein shown the rock-shafts H and I are mounted on a separate bent plate K, which constitutes a base or support for the several parts through which the indicating-arm is actuated and which is adapted for connection with the base-plate D', which is usually present on an Oliver type-writer. Said bent plate K is shown as having a base portion k, which fits upon the top of the base-plate D' and an upright part k', adjacent to the platen. Said base portion k is provided with screw-holes k² k³, through which may be inserted screws k⁴, which enter the base-plate D' and serve to secure the plate K to said base-plate. The said base portion k of the bent plate K is shown as provided with a notch k⁴, the sides of which straddle the lugs d' on said base-plate and serve to hold in place and steady the plate K.

The rock-shaft H is mounted in the plate K as follows: The lower end of said rock-shaft passes through a bearing-aperture in the horizontal base portion k of said plate, while the upper part of said rock-shaft has bearing in an outwardly or forwardly extending lug k⁵, formed on the upper margin of the upright part k' of said plate K. The spring J in this construction is coiled around the lower end of the rock-shaft H, which projects below the base part k and bears against or is connected at its free end with a pin j, secured in the said base-plate, as clearly seen in Fig. 7.

The rock-shaft I is shown as having bearing in lugs k⁶ k⁷, formed by bending upwardly projections on the side faces of the said base portion k of the plate K. The stop-arm h² on the rock-shaft H in this construction is adapted to bear against the upper part of the upright portion k' of the said plate K.

The indicating-arm h is made of such length that its point will extend to the lower edge of the printed line, the same reaching somewhat beyond the rear edge of the scale-bar. In the operation of the machine as the actuating-rod F moves upwardly, this movement always taking place as the type-arm is swung toward the platen, the arm i' is moved upwardly, thereby rocking the shaft I and through the connection described also moves the shaft H so as to swing the indicator-arm h away from the printing-point, as shown in dotted lines in Fig. 2. When the actuating-rod drops back to its normal position, however, the indicating-arm returns to a position at right angles to the platen, with its point opposite or in line with the printing-point. In other words, in the normal condition of the parts the end of the indicating-arm will indicate exactly where the type will strike on the next stroke; but when the ribbon is carried over the printing-point and the impact of the type occurs then the indicating-arm is swung away from its normal position and will not interfere with the stroke of the type against the platen in the making of the impression.

In the Oliver type-writer machine as heretofore constructed the printing-point of the type is indicated on the platen by a stationary arm which extends transversely of the platen over the latter and the graduated scale-bar. This arm cannot be set to register exactly with the printing-point, because its location in position to do so would interfere with the striking of the type against the platen. The said arm is therefore placed a short distance to one side of the printing-point, with the result that it is somewhat difficult for even a trained eye to determine the exact printing-point with any considerable degree of accuracy. By my construction, as above described, the above objections to the indicating-arm as heretofore constructed are entirely avoided, it being obvious that when the indicating-arm h is in its normal position or at times other than when the printing-strokes are being made and the ribbon is advanced over the printing-point, said indicating-arm will always point exactly to the printing-point and will enable the position of the same to be exactly determined.

It will be seen that the device described is cheap and simple of construction, will not readily get out of order, and can be readily applied to an Oliver type-writer or other type-writer of similar character.

So far as the broader aspects of my invention are concerned the indicating-arm *h* may be moved out of the path of the type by other means and in other manner than here shown.

I claim as my invention—

1. The combination with a platen, a horizontally-movable ribbon-guide and a supporting-arm for the ribbon-guide which rises in front of the platen, of an upright rock-shaft mounted on the said supporting-arm and provided with a laterally-swinging indicating-arm which projects over the platen, a spring applied to hold the indicating-arm in its normal position and connections between the said rock-shaft and the ribbon-guide whereby the indicating-arm is thrown laterally from its normal position when the ribbon-guide is advanced over the platen.
2. The combination with a platen, a horizontally-movable ribbon-guide, a supporting-arm for the ribbon-guide which rises in front of the platen, and actuating means for the ribbon-guide including a horizontal rock-shaft provided with a crank-arm and an upright connecting-rod engaging said crank-arm, of an upright rock-shaft mounted on the supporting-arm and provided with a laterally-swinging indicating-arm which projects over the platen, a spring holding the indicating-arm in its normal position, a second rock-shaft provided with a crank-arm to which oscillatory motion is transmitted from the said connecting-rod, and operative connections between said second horizontal shaft and the said upright shaft whereby oscillatory movement is transmitted from one to the other.
3. The combination with a platen and a

supporting-arm rising in front of the platen, 40 of an upright rock-shaft provided with an indicating-arm which extends over the platen, and with a stop-arm, a second rock-shaft arranged at right angles to the first one and provided with a rigid actuating-arm, said rock- 45 shafts having arms which engage each other, a spring acting on the upright rock-shaft to throw the indicating-arm toward the printing-point, and a reciprocating member operated by a part of the type-writing machine 50 which is moved in printing and which acts on the said actuating-arm of the second rock-shaft.

4. In a type-writing machine, the combination of an automatically-actuated ribbon- 55 vibrator, a printing-point indicator independent of said vibrator and normally in the indicating position, and means for automatically moving said indicator away from the indicating position when the vibrator moves 60 the ribbon to the printing-point.

5. In a type-writing machine, the combination of an automatically-actuated ribbon-vibrator; and an automatically-actuated printing-point indicator independent of said 65 vibrator and normally in the indicating position and adapted to be moved to the non-indicating position by the means for actuating the ribbon-vibrator.

In testimony that I claim the foregoing as 70 my invention I affix my signature, in presence of two witnesses, this 28th day of March A. D. 1904.

FRANK P. SHEPARD.
